UNITED STATES PATENT OFFICE.

GARDNER L. MORRISON, OF BROOKLYN, AND GEORGE D. SANFORD, OF PEEKSKILL, NEW YORK.

MANTEL-STOVE.

SPECIFICATION forming part of Letters Patent No. 426,393, dated April 22, 1890.

Application filed November 27, 1888. Serial No. 292,165. (No model.)

To all whom it may concern:

Be it known that we, GARDNER L. MORRISON and GEORGE D. SANFORD, citizens of the United States, and residents, respectively, of the city of Brooklyn, in the county of Kings, and the village of Peekskill, in the county of Westchester and State of New York, have invented certain Improvements in Portable Fire-Place Stoves or Heaters, of which the following is a specification.

Our invention relates to fire-place stoves or heaters; and it consists of certain details, hereinafter fully described, whereby such a stove or heater may be connected with the ordinary fire-place without previous preparation of the fire-place, or be set up against a chimney provided with an ordinary smoke-hole and have all the appearance of a regular fire-place heater made as now in common use.

Referring to the drawings, which form a part of this specification, Figure 1 is a front elevation of our stove, representing it as having the fire-piece attached. Fig. 2 is an elevation showing the back of the stove with the fire-piece removed. Fig. 3, Sheet 2, is a side elevation indicating the relative positions of the feeder, fire-pot, and smoke-flues, and also the plainness of the back of the stove. Fig. 4, Sheet 2, is a vertical cross-section through the center of the stove, taken sidewise. Fig. 5 represents the plan of the bottom of the stove. Fig. 6 is a cross-section through the line o'' of Fig. 4 and partly through line o''' . Fig. 7 represents a cross-section through the line o'''' , Figs. 3 and 4.

Referring to Fig. 1, it will be observed that the stove consists of the usual parts: the cover A, closing the mouth of the feeder H, which is suspended in the combustion-chamber B B', a fire-pot G, surrounded by a grating C, and an ash-pit D. The feeder is represented as broken away to show the location of a flue k and damper I back of the feeder. Upon each side of the fire-pot G flues K are shown, which give communication from the fire-chamber B' to the chambers $o' o'$ on each side of the ash-pit. Underneath the ash-pit is located the casing E, having an opening b in its front. The chambers that are closed by the panels $h h$ extend to the rear of the

stove on each side of the ash-pit. At their rear ends they are surmounted by pipes L L, Fig. 2, which rise parallel with the front pipes K K; but they meet in an arch over the top of the chamber B', where they unite in a common flue, which has an opening k into the chamber B', Fig. 1, and a rear opening l , Fig. 2, corresponding to an ordinary pipe-hole. The flue k is provided with a damper I, which is shown to be open and is operated by the lever J at the left side of the top B. The pipe-hole l is also provided with a damper m , which is operated by the lever i.

Fig. 2 represents the back of the stove without the fire-piece A'. The broken lines $n n'$ indicate the subdivisions of the ash-pit box D, o representing the ash-pit and $o' o'$ the chambers closed in front by the panels $h h$, Fig. 1. $p p$ are openings from the passages Q Q, to be connected with the chimney for the purposes of ventilation. The passages Q Q, made by the partitions $u u$, have side openings, as shown at b' , Fig. 3.

By reference to Fig. 4 it will be seen that the fire-pot G is surmounted by the back fire-plate M, which, with the plate N in the chamber B, divides the stove above the line X into two compartments. The forward compartment comprises the cavity of the fire-pot and the chambers B' and B. It will be observed that if the damper I be open the products of combustion will have a direct pathway to the chimney through the flues K and l. When the said damper is closed, the pathway will be as indicated by the line 1—that is, in through the ash-pit, up through the fire-pot, where it will divide to the right and left and pass down through the flues K, backward through the chambers o , upward through the pipes L L, and thence to the chimney through the outlet l.

Fig. 6 represents the ash-pit and its surroundings. Z' is the top on which the fire-pot rests, and contains the openings for the insertion of the pipes K and L. The figure shows one-half of plate Z' to be cut away, indicating the arrangement of partitions underneath it.

The base E of the stove is divided, as shown in Fig. 5, into the ventilating-compartments 100

Q and the central compartment P. The inlet to the latter is shown at b, Fig. 1, the outlet at S, Fig. 5. Air from the room is admitted through these passages to contact with 5 the heated parts of the stove, as indicated by line 2, Fig. 4.

Particular attention is directed to the plain back of this stove, as indicated particularly in Figs. 3 and 4. It may be used with or 10 without the back plate A'.

Having described our invention, what we claim, and desire to secure by Letters Patent, is—

1. A stove or fire-place heater having direct 15 and indirect smoke-flues, a smoke-escape opening at the rear, communicating with the flues, a flat rear wall, an air-flue extending from the base to the top between the rear wall and the rear wall of the combustion-chamber, 20 and flanges at the sides and top, arranged

substantially in the same plane as the rear wall, substantially as described.

2. A stove or fire-place heater having direct and indirect smoke-flues, a smoke-escape opening at the rear, communicating with the 25 flues, a flat rear wall, an air-flue extending from the base to the top between the rear wall and the rear wall of the combustion-chamber, side ventilating-passages to communicate with the chimney, and flanges at 30 the sides and top, arranged substantially in the same plane as the rear wall, substantially as described.

In testimony whereof we affix our signatures in presence of two witnesses.

GARDNER L. MORRISON.

GEORGE D. SANFORD.
